INKING ROLLER

Frederick Lamatsch, Grantwood, N. J., assignor
to R. Hoe & Co., Inc., New York, N. Y., a corpora-
tion of New York; Irving Trust Company,
receivers

Application June 18, 1931. Serial No. 545,330

3 Claims. (Cl. 308—190)

This invention relates to inking rollers for use upon printing presses, and while it pertains particularly to form rollers, it will be understood that the inventive idea may equally as well be carried out in any of the other rolls of the inking chain.

An object of the invention is to provide means of an improved nature in the construction and mounting of the roller whereby its efficiency is increased, the power necessary in its operation is reduced, and the weight of the entire roller assembly is minimized.

A further object of the invention is to construct the roller in such manner as to insure ease of assembly as well as to provide for proper and accurate alignment and adjustment.

With these objects in view, together with others which will appear as the description proceeds, the invention consists in the novel construction, combination and arrangement of parts all as will be described more fully hereinafter, illustrated in the drawing and particularly pointed out in the claims.

In the drawing:—

25 Fig. 1 is a fragmentary longitudinal sectional view taken through an inking roller constructed in accordance with the invention, and

30 Fig. 2 is a similar view illustrating the supporting shaft as it will appear prior to finishing and measuring operations.

As is well known in the printing art, the present type of inking rollers involves the use of rolls mounted upon anti-friction bearings to reduce as much as possible friction and to reduce the amount of power necessary in driving the machine. A particular advantage in the use of anti-friction bearings in the form roller is to insure easier rotation and lessen the liability of slippage of the roller as it contacts the form. Rollers of this character have been used with considerable success, but have been attended by certain disadvantages which the present invention seeks to overcome. Chief among these is the objection that the supporting shaft and roller shell spring or become distorted relative to each other, the result of which is obvious. In other instances this objection results in loosening of the supporting parts of the roller.

35 In carrying out the present invention, use is made of a tubular swaged central shaft for the support of the inking cylinder, the said shaft being machined at proper places for the application of anti-friction bearing members, while the cylinder ends are equipped with novel heads or 40 couplings for properly supporting the cylinder and

affording proper accommodation for the anti-friction bearing members.

Referring now more particularly to the drawing, the swaged central supporting shaft is shown generally in Fig. 2, and is indicated at 3. This shaft is hollow from end to end, and the medial portion thereof is preferably of larger diameter than the end portions, the latter being indicated at 4. It will be understood, of course, that the material of which the central supporting shaft is 45 constructed will be of sufficient size and strength as will withstand the strain to which it will be subjected when in use.

The shaft has its ends 4 machined as indicated in Fig. 1, a substantial distance inwardly from 50 its ends to provide a true outer periphery for proper support in posts or fixed bearing members indicated generally at 5. The shaft at a proper distance inwardly from each end is machined so as to provide annular seats 6 for the 55 accommodation of the inner race 7 of a conventional form of anti-friction bearing. The outer race 8 of the bearing is accommodated properly within a machined recess in the inner end of a cap 9 removably secured as by bolts 10 to the outer 60 end of a head 11 carried by the cylinder body 12 of the inking roller. This roller is faced as at 13 with rubber or similar resilient covering. The heads 11 have portions 14 which are received within annular internal recesses at the ends of 65 the shell or cylinder 12, and to rigidly secure the shell and heads together, welding may be applied as at 15.

The caps 9 are preferably each provided with an inwardly extending flange 16 to closely approach fixed portions of the central supporting shaft, and may be equipped with packings at 17 to retain lubricant as well as to exclude dirt and dust.

70 One end of the shaft is provided with a retaining block 18, which comprises a sleeve slidable upon the central shaft and which may be locked rigidly in position by a set screw 19. This sleeve is provided with a reduced portion 20 to engage within the portion 16 of the cap 9 and also cooperate with the adjoining anti-friction member to retain the same in place.

75 By constructing the central shaft and its cooperating parts in the manner described, it is apparent that the total weight is greatly reduced, 80 the mechanism is simplified and yet ample strength of the assembly is assured.

The central supporting shaft may be simply and economically produced by swaging processes and the open ends of the shaft permit of the 85

application of bars to facilitate lifting or carrying the rollers. The shell or cylinder 12 may be easily and quickly applied to the shaft, and the sleeve 18 locks the same with its associated parts in proper position. Should replacement or adjustment of any of the parts be required, it is apparent that the assembly permits of ready dismantling for these purposes. Should any looseness or wear develop in the bearing rings, the caps 9 may be readily withdrawn and replaced with new ones at a minimum expense and with the expenditure of little trouble or time.

Having thus described my invention, I claim:—

1. In an inking roller, a supporting shaft, anti-friction bearing races in spaced relation on said shaft, a cylinder enclosing said shaft, a head for each end of said cylinder, each head having an annular recess in its outer end disposed outwardly beyond the ends of said cylinder, a cap for each head, an annular projection on each cap engaged in the recess of its adjacent head, seats in said caps for said bearing races, said races disposed between said heads and caps, and means for detachably securing said caps to said heads.

25

2. In an inking roller, a supporting shaft, a shoulder on said shaft, a cylinder enclosing said shaft, the end of the cylinder disposed inwardly of said shoulder, a head on said cylinder having its outer end in radial alinement with said shoulder, a ball race enclosing said shaft and engaging said shoulder, a second race engaged with said head, antifriction elements between said races, and a cap detachably secured to said head and holding said second race against outward movement on said shaft.

80

3. In an inking roller, a supporting shaft, a shoulder on said shaft, a cylinder enclosing said shaft, a head on said cylinder having its outer end in radial alinement with said shoulder, a ball race enclosing said shaft and engaging said shoulder, a second race engaged with said head, antifriction elements between said races, a block on said shaft holding said ball race against outward movement on said shaft, and a cap detachably secured to said head and holding said second race against outward movement.

85

4. In an inking roller, a supporting shaft, a shoulder on said shaft, a cylinder enclosing said shaft, a head on said cylinder having its outer end in radial alinement with said shoulder, a ball race enclosing said shaft and engaging said shoulder, a second race engaged with said head, antifriction elements between said races, a block on said shaft holding said ball race against outward movement on said shaft, and a cap detachably secured to said head and holding said second race against outward movement.
